UNITED STATES PATENT OFFICE.

FREDERICK V. YOUNG, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,248,979.

Specification of Letters Patent. Patented Dec. 4, 1917.

Application filed February 17, 1917. Serial No. 149,214.

To all whom it may concern:

Be it known that I, FREDERICK V. YOUNG, a citizen of the United States, residing at Newark, in the county of Essex and State 5 of New Jersey, have invented certain new and useful Improvements in Telephone-Exchange Systems, of which the following is a full, clear, concise, and exact description.

This invention relates to telephone 10 exchange systems, and more particularly to such systems of the central energy type.

The object of this invention is the production of improved signaling means for such 15 telephone exchange systems.

15 In accordance with a feature of this invention, each end of a link circuit is provided with a relay initially controlled by a listening key and coöperating with a supervisory relay to cause the intermittent 20 operation of a supervisory signaling device.

This invention is illustrated in the accompanying drawing, in which all apparatus is shown in its normal and unactuated condition.

25 There is shown in the drawing a telephone exchange system containing one embodiment of this invention and comprising subscribers' lines A and B, terminating at a central office, and a cord circuit C thereat 30 for connecting the subscribers' lines. It will be understood that a plurality of lines, similar to A and B, terminate at the central office, but, for the sake of simplicity, only the two lines are shown. It is believed that the invention will be fully 35 understood from a description of the operation of the system shown in the drawing, and it will be so described.

Assuming that subscriber A desires to be 40 connected to subscriber B, A will signal the central office in the usual manner, whereupon the operator will insert the answering plug of cord circuit C into the jack associated with line A. The normal contacts 45 of the jack will be thereby opened, causing the release of line relay 5 to retire the line signal. The supervisory relay 6 also operates, and if the listening key 7 has not been actuated, answering supervisory lamp 8 will 50 be intermittently operated to furnish a signal to the operator. The operating circuit for the answering supervisory lamp 8 may be traced from battery through interrupter 9, lower normal contact of relay 10, left- 55 hand normal contact of relay 11, alternate

contact of relay 6, lamp 8, and sleeve contacts of the answering plug and jack to ground. Upon the operation of the listening key, the operator's telephone set is connected to the tip and ring strands of the 60 cord circuit, and relays 10 and 11 are operated over a circuit from battery through the right-hand winding of relay 11, lower winding of relay 10, and contact 12 of listening key 7 to ground. The operation of these 65 relays opens the circuit including the interrupter 9 and lamp 8, whereupon the lamp will cease to flash. Upon the operation of relay 11, a locking circuit is established therefor from battery through the 70 left-hand winding of relay 11, left-hand alternate contact thereof, alternate contact of relay 6, lamp 8, and sleeve contacts of the answering plug and jack to ground. The left-hand winding of relay 11 is of 75 high resistance so that when connected in series with the lamp 8, this lamp will not receive sufficient current to permit it to furnish a signal.

After conversing with the calling subscriber and upon being advised that subscriber A desires to be connected with the line of subscriber B, the operator restores the listening key to normal position and inserts the calling plug of the cord circuit C 80 into the jack of line B. Upon the restoration of listening key 7 to normal position, relay 10 releases, and upon the insertion of the calling plug into the jack of the line B, calling supervisory lamp 19 is lighted. The 85 operator may now signal subscriber B by actuating the usual ringing key 18. Subscriber B, in responding, causes the operation of supervisory relay 16, whereupon the lamp 19 is extinguished. The closure of the 90 alternate contact of relay 16, upon the operation thereof, does not include the interrupter 9 in circuit with the calling supervisory lamp 19, for the reason that relay 11 is now locked up and its right-hand contact 95 is open. The subscribers, upon finishing a conversation, restore the receivers to the switchhooks, whereupon supervisory relays 6 and 16 release. The release of relay 6 opens a locking circuit for relay 11, permitting 100 this relay to release. The release of these two supervisory relays also completes an operating circuit for each supervisory lamp, whereupon these lamps glow to furnish disconnect signals. The operator may 105 110

then withdraw the plugs from the jacks, whereupon all apparatus returns to normal.

Suppose, however, that before the plugs were withdrawn from the jacks, subscriber 5 A should desire to make a recall. Then the removal of the receiver from the switchhook by subscriber A causes the intermittent operation of the answering supervisory lamp 8 to furnish a signal to the operator. In 10 like manner, should subscriber B have desired to make a recall, the removal of the receiver from the switchhook by subscriber B causes the operation of supervisory relay 16 to connect interrupter 9 in circuit with 15 calling supervisory lamp 19, thereby causing the intermittent operation thereof. The operator, observing either of these signals, actuates the listening key to connect the telephone set to the cord circuit. The actuation 20 of the listening key causes the operation of relays 10 and 11, and a locking circuit will thereby be completed for one or both of these relays, depending upon whether one or both supervisory relays are operated. 25 Supervisory relay 6 controls the locking circuit of relay 11, and supervisory relay 16 controls the locking circuit of relay 10. The upper winding of relay 10 is of high resistance so that when connected in circuit with 30 lamp 19, the lamp will not receive sufficient current to permit it to furnish a signal. The operator, after conversing with the subscriber who has made the recall, may remove the plug of the cord circuit connected with 35 the other line, and complete connection with the line desired by the subscriber recalling. In this connection, it may be noted that each end of the cord circuit is similarly equipped so that either end may be employed as an 40 answering end and either end as a calling end.

What is claimed is:

1. A telephone exchange system comprising telephone lines, a link circuit for inter- 45 connecting the lines, a supervisory relay, a signaling device, a listening key, a second relay energized upon the actuation of the listening key, a locking circuit therefor including the signaling device and contacts of 50 the supervisory relay, and interrupter mechanism brought into circuit with the signaling device by the subsequent deenergization

of the second relay followed by the energization of the supervisory relay.

2. A telephone exchange system comprising 55 telephone lines, a link circuit for inter- connecting the lines, a supervisory relay for each end of the link circuit, a signaling device controlled by each supervisory relay, a listening key, a second and a third relay 60 energized by the actuation of the listening key, a locking circuit for the second relay including contacts of one supervisory relay and one signaling device, interrupter mechanism, and a circuit for the signaling device 65 and the interrupter mechanism including contacts of one supervisory, the second and third relays completed by the subsequent deenergization of the second relay and the energization of the one supervisory relay. 70

3. A telephone exchange system comprising 75 telephone lines, a link circuit connecting the lines, a supervisory and a coöperating local circuit relay for each end of the link circuit, a signaling device under control of each supervisory relay, a switching device for the link circuit, an operating circuit for the local circuit relays established upon the actuation of the switching device, interrupter mechanism and a circuit for each 80 signaling device and the interrupter mechanism containing contacts of both local circuit relays and its controlling supervisory relay.

4. A telephone exchange system comprising 85 telephone lines, a link circuit connecting the lines, a supervisory and a coöperating local circuit relay for each end of the link circuit, a signaling device under control of each supervisory relay, a listening key, 90 an operating circuit for the local circuit relays established upon the actuation of the listening key, an independent locking circuit for each local circuit relay controlled by each supervisory relay, interrupter mechanism and a circuit for each signaling device and the interrupter mechanism including 95 contacts of both local circuit relays and its controlling supervisory relay.

In witness whereof I hereunto subscribe 100 my name this 16th day of February, A. D. 1917.

FREDERICK V. YOUNG.
